(57) **CLAIM**

We claim the ornamental design for a forward camera system, as shown and described.

DESCRIPTION

FIG. 1 is a front perspective view of a forward camera system showing our new design;

FIG. 2 is a front elevational view of the forward camera system of FIG. 1;

FIG. 3 is a rear elevational view of the forward camera system of FIG. 1;

FIG. 4 is a right side elevational view of the forward camera system of FIG. 1;

FIG. 5 is a top plan view of the forward camera system of FIG. 1; and,

FIG. 6 is a bottom plan view of the forward camera system of FIG. 1.

The broken lines depict portions of a forward camera system in which the design is embodied and form no part of the claimed design.
